DESIGN FOR A DRAFTSMAN'S UNIVERSAL TEMPLATE

Alexander Lozier, Los Angeles, Calif.

Application November 2, 1943, Serial No. 111,575

Term of patent 7 years

To all whom it may concern:

Be it known that I, Alexander Lozier, a citizen of the United States, residing at 1025 South Orange Drive, in the city and county of Los Angeles and State of California, have invented a new, original, and ornamental Design for a Draftsman's Universal Template, of which the following is a specification, reference being had to the accompanying drawing, forming part thereof.

I claim:

The ornamental design for a draftsman's universal template, as shown.

ALEXANDER LOZIER.
